UNITED STATES PATENT OFFICE.

ARNE LINDE, OF MACRORIE, SASKATCHEWAN, CANADA.

WRENCH.

1,389,200.

Specification of Letters Patent. Patented Aug. 30, 1921.

Application filed September 4, 1920. Serial No. 408,400.

To all whom it may concern:

Be it known that I, ARNE LINDE, a citizen of the Dominion of Canada, residing at Macrorie, in the county of Moose Jaw and 5 Province of Saskatchewan, have invented certain new and useful Improvements in Wrenches, of which the following is a specification.

This invention relates to wrenches and 10 consists of a construction having a hollow handle with a movable head.

The object of my invention is to provide a wrench in which the head is so held in the handle that it can be positioned at different 15 relative positions thereto so as to allow the head to be turned to various angular positions for turning nuts which are difficult for the ordinary wrench to get a hold on.

A further object is to provide tension jaws 20 which control the position of the head relatively to the handle.

A further object is to provide a means for releasing these jaws as may be desired.

A further object is to provide a locking 25 means for holding the head in fixed position in said handle.

With these and other objects in view, the invention consists in the construction, combination and arrangement of parts as will 30 be hereinafter fully described, illustrated in the accompanying drawings, and pointed out in the claims hereunto appended.

Figure 1 is a plan view of my invention with the head in locked position relatively 35 to the handle.

Fig. 2 is a plan view of my invention the handle being shown in section.

Fig. 3 is a side view of the head, the handle being partly broken away.

40 Fig. 4 is a plan view of my invention showing the head in bent position.

Referring to the drawings, like numerals 45 designate like parts in the various drawings.

5 indicates a handle having a hollow center 6 which hollow center forms an enlarged opening or mouth 7 at one end and an enlarged opening 8 at the opposite end. Positioned in the opening 7 are the jaws 9 and 10 on their respective pins 11 and 12. These 50 jaws are tensioned apart at their inner end by a coil spring 14.

15 is a head pivotally connected on the pin 16 and tensioned thereto by a coil spring 17 which causes the outer end of the head to be tensioned in the direction of the arrow, Fig. 2, when the jaws 9 and 10 are released from controlling the same. The inner end of the head 15 is provided with notches on its opposite side adapted to coöperate with the outer ends of the jaws 9 and 10 60 so as to hold the head 15 in at least three different relative positions to the handle 5. It will be seen that the notches are so formed that the head can be turned opposite to the direction of the arrow and the outer 65 ends of the jaws 9 and 10 will engage in the next respective notch. When it is desired to allow the head to turn in the direction of the arrow, a rod 18, which passes through the hollow center 6, is pressed inwardly. 70 This rod is provided with a button 19 at its outer end and a bifurcated end 20 at its inner end, which bifurcated end fits over the outer sides of the inner end of the jaws 9 and 10 so that when the rod 18 is pressed 75 inwardly the inner ends of the jaws 9 and 10 are pressed inwardly against the tension of the spring 14, but at the same time releasing the outer ends from the notches in the head 15. The spring 17 then turns the 80 head in the direction of the arrow, Fig. 2.

In some cases it will be found more satisfactory to have the head in fixed position to the handle, and to provide locking means for the head, I use a sliding member 22 85 which carries a pin 23, which pin is adapted to engage in a notch 24 on the inner end of the head 15 when the head is in straight outward position to the handle 5.

From the foregoing it is thought that the 90 construction of my invention will be clearly understood, and, therefore, a more extended explanation has been omitted.

What I claim as new is:

1. A wrench consisting of a handle, a head 95 pivotally mounted in one end of said handle, tension means holding said head at an angle to said handle, a means for locking said head at a different angle to said handle and a means for operating said locking means. 100
2. A wrench consisting of a handle, a head pivotally mounted in one end of said

handle, tension means holding said head at an angle to said handle, a means for locking said head at a different angle to said handle, a means for operating said locking means and a means for locking said head in straight outward position relative to said handle.

In testimony whereof I affix my signature in the presence of two witnesses.

ARNE LINDE.
